[57] CLAIM

The ornamental design for a chair, as shown and described.

DESCRIPTION

FIG. 1 is a front elevation view of a chair showing my new design, the recessed areas are shaded for color contrast;

FIG. 2 is a side elevation view thereof, the undisclosed side being substantially identical with the side shown, the recessed areas are shaded for color contrast;

FIG. 3 is a rear elevation view thereof, the recessed area is shaded for color contrast;

FIG. 4 is a cross-section taken on line 4—4 of FIG. 2, the recessed area is shaded for color contrast;

FIG. 5 is a cross-section taken on line 5—5 of FIG. 2, the recessed areas are shaded for color contrast; and

FIG. 6 is a cross-section taken on line 6—6 of FIG. 3.

FIG. 1

FIG. 2
